UNITED STATES PATENT OFFICE.

ELEFA B. JOHNSON, OF SACRAMENTO, CALIFORNIA.

AUTOMOBILE WASHER AND DRIER.

Application filed January 28, 1925. Serial No. 5,381.

To all whom it may concern:

Be it known that I, ELEFA B. JOHNSON, a citizen of the United States, residing at Sacramento, county of Sacramento, State of California, have invented certain new and useful Improvements in Automobile Washers and Driers; and I do declare the following to be a full, clear, and exact description of the same, reference being had to the accompanying drawings, and to the characters of reference marked thereon, which form a part of this application.

This invention relates to improvements in devices for cleaning flat polished surfaces and especially automobile bodies and the enameled parts associated therewith.

The principal object of my invention is to provide a device of this character by means of which dirt removing, washing and drying operations may be carried out with a single implement and practically at one and the same time.

Another object is to provide a device for the purpose so constructed that it may be easily operated by any person with but very little effort and no previous experience being necessary.

A further object is to arrange the cleaning and drying elements of the device in such a manner that they may be readily removed and replaced when worn out without having to discard the entire implement.

A still further object is to construct a device so that its use will not scratch, mar or damage in any way the most highly polished or enameled surface.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side view of the device partly broken out and showing the same as connected to an ordinary garden hose.

Fig. 2 is a bottom plan view of the device.

Referring now more particularly to the characters of reference on the drawings, the numeral 1 denotes a hollow body preferably of substantially rectangular form and made

of any suitable material and in any desired size. The body has transverse and longitudinally spaced grooves 2 in the under side thereof to receive flexible rubber squeegee strips 3 which project outwardly from said under side of the body as well as beyond the side edges thereof for a certain distance.

Projecting outwardly from the upper or outer face of the body at an acute angle 2 and adjacent one end thereof is a neck 4 adapted for connection to a stop cock 5 to which in turn a hollow rigid handle 6 is attached. The outer end of the handle has a coupling member 7 to enable connection to be detachably made with one end of an ordinary flexible garden hose 8.

The under face of the body between the strips 3 is provided with a plurality of perforations 9 of suitable size. These perforations however are preferably omitted between those two of the members 3 which are at the end of the body farthest from the handle 6, or at what may be considered the upper end of the body.

The grooves are preferably dove-tailed in cross-sectional form, while the members 3 have corresponding longitudinal flares along one edge. In this manner the strips 3 may be slid into the grooves from the ends thereof and are held without the use of cement. They cannot be displaced by pulling the same straight away from the body and yet they may be readily removed and replaced when necessary, as in case of wear or other deterioration.

In operation water is turned into the hose 8 from the usual hydrant and its flow to the body is thereafter controlled by the stop-cock 5, so that the water may pass through the orifices 9 with whatever force is deemed desirable, depending on conditions.

The operator grasps the handle 6 and while the water is flowing reciprocates the body back and forth in a plane at right angles to the strips 3, with the latter in engagement with the surface to be cleaned. This operation causes any dirt on the surface to be loosened and the water will then wash said dirt away.

When the surface is cleansed of dirt and it is desired to dry same the body is tilted so that all the strips 3, except that one at the upper end which is isolated from the water spray, are held away from the surface being worked on. The body is then drawn vertically and down with said single strip 3 in firm engagement with the surface, caus-

ing any water to be drained therefrom in the well known manner as employed in connection with the ordinary squeegee devices.

This drying operation, as above set forth, 5 may be carried out without turning off the water, so that washing and drying operations may be done in practically simultaneous and follow-up order. If desired, however, the water may be shut off at the cock 10 5 and all the strips 3 used for drying purposes.

These strips 3, projecting as they do beyond the side edges of the body, the surface being acted on is protected from contact with 15 said body if the latter should be accidentally turned on edge.

The handle 6 being disposed at one end of the body at an acute angle thereto, the main portion of the body may readily be projected 20 into restricted areas, as for instance between the fender and hood of an automobile.

From the foregoing description it will be readily seen that I have produced such a device as substantially fulfills the objects of 25 the invention as set forth herein.

While this specification sets forth in detail the present and preferred construction of the device, still in practice such devia-

tions from such detail may be resorted to as do not form a departure from the spirit of 30 the invention, as defined by the appended claims.

Having thus described my invention what I claim as new and useful and desire to secure by Letters Patent is:

35

1. A washing and drying device comprising a hollow body member having spaced parallel transverse grooves in one face thereof, and resilient strips mounted in the grooves and projecting outwardly from the 40 body, said body being perforated between the grooves.

2. A washing and drying device comprising a hollow body member, resilient strips projecting outwardly from one face thereof in spaced relation to each other, said body being orificed between the strips, a hollow handle attached to and communicating with the interior of the body, and adapted at its 45 outer end to be connected to a source of 50 water supply, and a stop cock at the body end of the handle.

In testimony whereof I affix my signature.

ELEFA B. JOHNSON.
